UNITED STATES PATENT OFFICE.

NATHAN J. GOODMAN, OF ST. LOUIS, MISSOURI

LAUNDRIED-SHIRT PROTECTOR.

1,107,513.

Specification of Letters Patent. Patented Aug. 18, 1914.

Application filed February 1, 1913. Serial No. 745,728.

To all whom it may concern:

Be it known that I, NATHAN J. GOODMAN, a citizen of the United States, and resident of St. Louis, Missouri, have invented certain new and useful Improvements in Laundried-
5 Shirt Protectors, of which the following is a specification containing a full, clear, and exact description, reference being had to the accompanying drawings, forming a part hereof.

10 My invention relates to improvements in laundried shirt protectors, and the object of my invention is to construct a protector for laundried shirts of the type employing a thin, transparent sheet of paper through 15 which the pattern of the shirt is visible, and a relatively thick backing which protects the shirt.

In this improved construction especial attention is directed toward the backing which is arranged to have integral flaps which are secured to each other and whatever securing means is employed also secures in place the thin transparent sheet. By this arrangement the cost of assembling is reduced to a minimum and a decided advantage ensues for the reason that the protector has its side margins formed of the backing instead of relying upon the relatively thin transparent sheet.

30 With the above purposes in view my invention consists in certain novel features of construction and arrangement of parts as will be hereinafter described and illustrated by the accompanying drawings, in which—

Figure 1 is a plan on a reduced scale of one of my improved shirt protectors having a shirt therein, the uppermost corners of the protector being shown in section; Fig. 2 is 40 a transverse sectional view on the line 2—2 of Fig. 1, the shirt being omitted; Fig. 3 is an edge view of the complete device; and Fig. 4 is a perspective on a reduced scale showing the mouth of the protector extended 45 to receive a shirt.

Referring by numerals to the accompanying drawings: 5 designates the body portion or back of my improved shirt protector. This body portion is substantially rectangular and is of a length equal to the average 50 length of laundried shirts and of a width as great as the maximum width of ordinary shirts. Carried by the side margins of the backing 5 and preferably formed integral therewith, that is out of the same piece of material, are the flaps 6. In order that the

flaps 6 may be pressed against the body of the backing 5, the line 7 of articulation between the backing and the flaps is creased. At their approximate longitudinal centers 60 the flaps 6 have widths substantially, but not fully, half the width of the backing 5 so that, when the flaps are folded over the backing, their margins at their longitudinal centers will be adjacent each other.

65 8 designates a gummed seal which is arranged to connect the flaps 6. The flaps 6 each converge from their longitudinal centers toward the ends of the protector and at one end of the protector there are the 70 slots 9 on the lines 7 between the flaps 6 and the backing 5.

10 designates the sheet of paper which is transparent and whose dimensions are approximately the dimensions of the backing 5. 75 This sheet of transparent paper is secured only at its center by being adhesively secured to that portion of the gummed seal lying between the margins of the flaps 6.

80 By reason of the transparency of the sheet 10 and the formation of the flaps 6, the pattern or style of a shirt inclosed in the wrapper may be visible and determined without dismantling the protector and without moving the shirt lengthwise through the wrapper 85 to expose the end thereof.

85 By the provision of the slots 9 between the backing and the flaps at one end of the protector, the insertion of a shirt in the protector is facilitated and accomplished without 90 danger of tearing the body of the protector on the folding lines.

95 For the reason that the body, or the backing and flaps, is in one piece covering the sides of the protector, tearing out of the sides of the protector is entirely eliminated, and for the reason that the thin transparent sheet is unsecured at its margin the tearing or destruction of the said sheet is reduced to a minimum.

100 Heretofore it has been the practice to secure the margins of the transparent sheet to the margins of the backing, hence when a shirt, or the like, was inserted in a protector as much strain was placed upon the transparent sheet as upon the backing, which very frequently resulted in the tearing of the transparent sheet. A distinct advantage in 105 my improved construction lies in the fact that the single gummed seal serves to connect the flaps and also secure the transparent sheet in place.

Heretofore protectors were made with a thin sheet and a relatively thick, inflexible sheet, the margins of which were connected by gumming. The backing sheet of my improved construction is more or less flexible, so that a protector having a shirt therein may be folded or rolled as desired.

I claim:

- 10 1. A laundried shirt protector, comprising a backing having opposite marginal flaps, a seal uniting said flaps, and a transparent sheet secured to said seal and having its margins free from said backing and flaps.
2. A laundried shirt protector, comprising

a backing having marginal side flaps, identical in size and shape, the greatest width of each of which is less than half the width of the backing, a transparent sheet detached from said backing and flaps, and a seal for uniting said flaps at their widest portions and holding in place said transparent sheet.

In testimony whereof, I have signed my name to this specification, in presence of two subscribing witnesses.

NATHAN J. GOODMAN.
